Charles E. Jones, Chicago, Ill., assignor to Nathan R. Sklar, Chicago, Ill.

Application September 8, 1948, Serial No. 148,503

Term of patent 14 years

(Cl. D31—4)

To all whom it may concern:

Be it known that I, Charles E. Jones, a citizen of the United States, residing at Chicago, county of Cook, State of Illinois, have invented a new, original, and ornamental Design for an Animal Trap or the like, of which the following is a specification, reference being had to the accompanying drawings, forming a part thereof.

In the drawings:

Fig. 1 is a side elevational view of an animal trap or the like, showing my new design.

Fig. 2 is a top plan view thereof.

Fig. 3 is a front elevational view thereof.

Fig. 4 is a rear elevational view thereof.

I claim:

The ornamental design for an animal trap or the like, as shown.

CHARLES E. JONES.
